FUSEE

Franklin W. Olin, Alton, Ill., assignor to The
Equitable Powder Manufacturing Company,
East Alton, Ill., a corporation of Delaware

Application July 5, 1946, Serial No. 681,469

10 Claims. (Cl. 102—37.8)

1

This invention relates to fuses or colored-light torches of the type used for signal purposes.

The ordinary fusee, which consists of a cylindrical charge of pyrotechnic composition having a match head at its upper end, is provided with a closure cap, on the radial end face of which a scratch composition, including friction material, is arranged. The closure cap is adhered to the body of the fusee so as to conceal and protect the match head. When it is desired to ignite the fusee, the closure cap is removed by twisting the cap relative to the fusee body until the adhering wrapper ruptures, whereupon the cap is removed and, after exposing the scratch material on the end of the cap, the latter is manipulated in engagement with the match head of the fusee, so as to ignite the latter. In this manipulation of the parts leading to ignition, the closure cap with its scratch surface is necessarily held in such position that the hand is in the path of fire which will result upon ignition of the fusee. Oftentimes workmen have been burned while manipulating a fusee in this manner to ignite the same.

One object of the invention is to provide a fusee which may be ignited with certainty, facility, and safety.

Another object of the invention is to provide a fusee closure having adequate protective characteristics but withal more economical to manufacture and assemble than those heretofore employed.

Other objects and advantages will become apparent from the following detail description and accompanying drawings, in which:

Figure 1 is a perspective view of a fusee illustrating one embodiment of the invention as it appears when ready for the market;

Figure 2 is a longitudinal section of the embodiment of the fusee shown in Figure 1;

Figure 3 is a perspective view illustrating the embodiment of Figure 1 with closure partially released;

Figure 4 is a perspective view of the fusee with the closure entirely removed and in striking position;

Figure 5 is a development view of a part of the closure removed from the fusee between the conditions illustrated in Figures 3 and 4; and

Figure 6 is a development view of a wrapper element.

In accordance with the present invention, the fusee, which, as usual, has a match head, is provided with an improved protective closure for the match head end of the fusee. The invention is characterized by the provision of a closure so con-

2

structed and arranged as to provide a cylindrical or partially cylindrical striking surface, which is normally enclosed and hence protected, but which, upon removal of the closure, becomes exposed for use as a striker for the match head of the fusee. An important aspect of the invention is the arrangement of said cylindrical striking surface about one end of an elongated closure member so as to provide a handle portion laterally remote from the striking surface. The striker may thus be manipulated without bringing the hand into a zone of the flame which results from the striking operation. The invention also contemplates that the striking surface be so coordinated with the closure structure that, upon rupture of the latter, the former is, with certainty, unobstructed by paper or other inert material which might otherwise become interposed between the striker and the match head.

Referring to the drawings for an illustrative embodiment of the invention, the fusee comprises a paper tube 1 closed at one end by a plug 2 having a spike 3. The plug 2 may consist of convolutions of paper. The end portion 4 of tube 1 is then folded over and crimped against plug 2, which is simultaneously compressed in a direction parallel to the axis of the tube to form a sturdy water-tight closure. The tube 1 is charged with combustible material 5, which may be any of the usual slow-burning pyrotechnic compositions. At the upper end of charge 5, a paper washer 6 is arranged and a match head 7 extends through the washer 6 into a cavity 8 in the charge 5 with a generous portion exposed above washer 6 for striking. The tube 1 is closed by crimping or turning the end thereof inwardly into washer 6 about match 7, as indicated at 9.

The closure for the upper end of the fusee which characterizes this invention includes a tube 10, which may be made of spirally wound paper or of cardboard. If desired, one end of the tube 10 may be closed by infolding or the provision of a suitable wad or plug therat, but such is not essential in the example shown in the drawings. Adjacent one end of tube 10, a band of friction material 11 is painted or adhered to the exterior of the tube. In the embodiment shown, and as preferred, the band of friction material is circumferentially continuous, but is confined to the region adjacent one end of the tube so as to leave a substantial length of tube between the band 11 and the opposite end of tube 10. A strip of protective material 12, such as textile fabric, is applied over the band 11 preferably without adhesion thereto. With the tubes 1 and 10 tele-

scoped, as shown in Figure 2, a sheet 13, which may be tissue paper, is wrapped about the tubes so as to substantially overlap both ends of tube 10. The sheet 13 is adhesively secured to tube 1 below the end of tube 10 and is adhesively secured to tube 10 above band 11 and tape 12.

A convenient procedure for effecting the desired relationship of the parts just described is to provide the wrapper-sheet 13 (having a length substantially in excess of the length of tube 10 and a width slightly in excess of the circumference thereof) with an adhesive coating on one side. The tape 12 is adhered to the sheet 13 with an extending tab 14, as shown in Figure 6, and in proper position on the sheet 13, so that when the latter is in the position shown in Figure 2, the tape 12 will marginally overlap the band of friction material 11. Having thus pre-assembled the sheet 13 and tape 12, the assembly may be applied over the telescoped tubes 1 and 10, as aforesaid, and so that the tab 14 of tape 12 is accessible outside the wrapping 13. The portion of sheet 13 which extends beyond the upper end of tubes 1 and 10 may be twisted together, as shown at 15, or otherwise infolded, while the adhesive coating is still active. The assembled fusee is then given a final water-proofing treatment by immersing it in paraffin or other suitable water-proofing agent.

In order to light or fire the fusee, the tab 14 is grasped and tape 12 ripped from the fusee in the manner shown in Figure 3, which operation uncovers the friction material 11 and removes a section of wrapper 13 beyond the edges thereof. This releases the tube 10 and the adjunct remainder of wrapper 13 from the tube 1. The tube 10 is then grasped at the top, slipped off the tube 1, and the fusee is ignited by rubbing the friction material 11 against the match 7. As shown in Figure 4, it will be observed that the tube 10 is sufficiently elongated that it may be grasped at a zone remote from the striker 11 and manipulated without bringing the hand into the path of the fire.

Since the friction material 11 completely encircles the cap 10, it is not necessary to turn the closure cap in the hand to locate the friction material 11, for instance, in the dark, and lighting of the fusee can be accomplished merely by rubbing the nearest side of the cap on the match 7. The band of friction material 11 encircling the cap need not be continuous, that is, the band may consist of closely spaced spots, stripes, or the like, substantially uniformly distributed around the cap, provided that the spaces between such spots or strips are not large enough to interfere with the striking of the match. Since the open end of tube 10, where the striker 11 is located, is quite flexible radially, it will distort under striking pressure so as to flatten the striker somewhat and thereby provide a sufficiently long stroke while the striker is in engagement with the match.

The unwinding of tape 12 is effective to tear the wrapper 13 between the friction material 11 and the portion of the wrapper adhering to the cap, as at 16. Thus torn edges of the wrapper 13 are prevented from hanging over the friction material, which would interfere with the match striking operation. Removal of tape 12 releases the cap from adhesive connection with the tube 1, and the cap can be easily slipped off the tube without any further tearing operation.

The tape 12 should be constructed with a tab portion 14 so that it can be readily grasped by

the fingers, for example, by extending beyond the outer edge of wrapper 13, as illustrated in Figure 1. Figure 4 illustrates the fusee after tape 12 has been removed and with the cap in position to strike the match. When the opening tape 12 is made sufficiently wide to cover the friction material 11 and lower edge of cap 10, in accordance with the embodiment illustrated, the entire wrapper 13 may be coated with adhesive, since tape 12 then prevents wrapper 13 from adhering to the friction material 11 and lower edge of cap 10. If a narrower tape is employed, care should be taken to prevent any adhering of the wrapper 13 to the friction material 11, for example, by omitting adhesive from this portion of the wrapper. For instance, the function of tape 12 may be accomplished by a string wound about the cap 10 between the friction material and that portion of the wrapper adhering to the cap in a position such as at 16, in which case adhesive is omitted from the wrapper between the string and bottom of the cap 10, so that the portion of the wrapper 13 covering the friction material 11 and lower edge of the cap 10 is retained on tube 1 when the string is pulled to circumferentially tear the wrapper at 16 and the cap 10 is slipped off the tube 1.

Although a crimp or twist closure, such as illustrated at 15, is preferred because of its simplicity and effectiveness, tube 10 may be closed at the top by means of a paper wad or other suitable device.

The invention accordingly provides an improved fusee, facilitating handling and use thereof, and eliminating many disadvantages extant with prior fusees. It is to be understood that the embodiment of the present invention as shown and described is merely illustrative, and that the scope of the invention is not to be limited thereby except as set forth in the appended claims.

Having thus described the invention, what is claimed is:

1. A closure for the match-end of a fusee comprising an elongated tubular cap, a band of friction material exteriorly encircling the axial wall of said cap near one end thereof.

2. In a fusee, a closure for the match-end of the fusee comprising a tubular cap, a band of friction material exteriorly encircling the axial wall of said cap, and a wrapper covering said friction material and securing said cap to said fusee.

3. In a fusee, a closure for the match-end of the fusee comprising a tubular cap, a band of friction material exteriorly encircling the axial wall of said cap adjacent one end thereof, a wrapper adhered to the fusee adjacent one margin of the friction material and adhered to said cap adjacent the margin of friction material, and an opening tape overlying the friction material beneath the wrapper, said tape having a tab portion exposed outside said wrapper.

4. In a fusee, a closure for the match-end of the fusee comprising a tubular cap, a band of friction material encircling the wall of said cap, an opening tape covering said friction material having an exposed tab portion, and a wrapper adhered to said tape, to said cap, and to said fusee holding said tape in position on said friction material and securing said cap to said fusee.

5. In a fusee, a closure for the match-end of the fusee comprising a tubular cap, a layer of friction material encircling said cap, circumferentially continuous adhesive securing said cap to

said tube, and means covering said friction material adapted upon removal to loosen said cap from said fusee.

6. A fusee comprising a tube charged with combustible material, one end of said tube being closed, a match composition at the other end of the tube in contact with the combustible material, a tubular cap covering the match-end of said tube, a band of friction material encircling the outer wall of said cap, a paper wrapper securing said cap on said tube, and a tape having a tab portion wound under said wrapper, said tape being adhered to the wrapper and adapted upon removal to circumferentially tear said wrapper, remove the overlying portion of the wrapper, loosen said cap from said tube, and expose said friction material.

7. A fusee comprising a tube charged with combustible material, one end of said tube being closed, a match composition in contact with the combustible material at the other end of said tube, a tubular cap covering the match-end of said tube, a band of friction material encircling and adjacent the open end of said cap, a paper wrapper adhesively holding said cap on said tube, and an opening tape wound about said cap under said wrapper having a tab portion exposed and adapted upon removal to tear said paper wrapper, loosen said cap from said tube, and expose said friction material.

8. A fusee comprising a tube charged with combustible material, one end of said tube being closed, a match composition at the other end of the tube in contact with the combustible material, a tubular cap covering the match-end of the tube, a band of friction material encircling said cap, a tape having a tab portion wound over said fric-

tion material and lower edge of said cap, and a paper wrapper holding said tape in position and holding said cap on said tube, said tape being adapted during removal to tear said wrapper, uncover said friction material, and loosen the cap from the tube.

9. A fusee comprising a tube charged with combustible material, one end of said tube being closed, a match composition contacting the combustible material at the other end of the tube, a cap covering the match-end of said tube, a band of friction material encircling the wall of said cap, a wrapper securing said cap to said tube, and an opening tape under said wrapper having an exposed tab.

10. In a fusee, a closure for the match-end of the fusee comprising a tubular cap, a band of friction material exteriorly encircling the axial wall of said cap, a readily tearable paper wrapper covering the friction material and adhered to the cap and the fusee at opposite edges of said band, and a textile tape relatively stronger than said paper wrapper interposed between said wrapper and said band, said tape being adhered to said wrapper beyond the edges of said band.
